UNITED STATES PATENT OFFICE.

ANDREW JOHNSON, OF GREENSBOROUGH, ALABAMA.

BALING-PRESS.

SPECIFICATION forming part of Letters Patent No. 296,014, dated April 1, 1884.

Application filed December 13, 1883. (No model.)

To all whom it may concern:

Be it known that I, ANDREW JOHNSON, of Greensborough, in the county of Hale and State of Alabama, have invented a new and useful Improvement in Baling-Presses, of which the following is a full, clear, and exact description.

Reference is to be had to the accompanying drawings, forming part of this specification, in which similar letters of reference indicate corresponding parts in all the figures.

Figure 1 is a sectional side elevation of my improved press. Fig. 2 is an end elevation of the same, parts being broken away. Fig. 3 is a sectional plan view of the same, taken through the line α α , Fig. 1. Fig. 4 represents a modified form of the fulcrum-bar. Fig. 5 is a side elevation of one of the guard-plates. Fig. 6 is an elevation of a separable link and ring.

The object of this invention is to facilitate the baling of cotton, moss, hay, and other substances, and also to promote convenience in operating baling-presses.

The invention consists in a baling-press constructed with slotted ends provided with ratchet-bars at the sides of the slots, and fulcrum-bars suspended near said ends. The press-box is provided with a follower strengthened by a truss, and carrying spring-held catch-bars to engage with the ratchet-bars. To the ends of the center bar of the follower are attached bands having rings at their bottoms and ribs at their tops for the operating-levers to engage with successively. The levers are made with slotted ends to engage with the fulcrum-bars, and with recesses upon the lower side of the said ends to engage successively with the rings and ribs of the bands. The rings of the bands are provided with separable links carrying rings for the levers to engage with when beginning the operation. The slots in the ends of the press below the follower are covered by plates interposed between the said ends and the ends of the lower part of the said follower, and which are forced down by the said follower to prevent the material being compressed from being forced out through the said slots, as will be hereinafter fully described.

50 A represents the frame of the machine.

B is the casing, the upper part of which is stationary, and is attached to the frame A.

C are the side doors, the lower edges of which are inserted between the side edges of

the stationary head-block D and bars attached to the base-frame. 55

E are the end doors, the lower edges of which are inserted in grooves formed in the end parts of the head-block D, or between cross-bars attached to the said end parts. The upper parts 60 of the end doors, E, are supported against outward pressure by bars F, placed in keepers G, attached to the posts of the frame A. The upper parts of the side doors, C, are supported against outward pressure by bars H, the projecting end parts of which are notched to the projecting end parts of the end bars, F. The ends of the press are slotted from their upper edges to the lower cross-bars to receive the projecting ends of the center bar of the follower, 65 hereinafter described. The parts of the ends weakened by the slots are strengthened by upright bars I, attached at their lower ends to the end cross-bars of the frame A, and at their upper ends to the inner ends of short cross-bars J, attached to the posts of the said frame A. The parts of the ends of the press weakened by the slots are further strengthened by separable cross-bars W, which are recessed upon 70 their lower sides to fit upon the tops of the said ends, and which are removed when the follower is to be put on or taken off. The end cross-bars, A', of the frame A are placed at a lower level than the side cross-bars, A'', of the said frame, so that the face of the follower K 75 can be lowered below the lower edge of the side casings, B, without making the said follower too deep. The ends of the center bar of the follower K project through the slots in the ends of the press, and the middle part of the 80 said bar is strengthened by the truss-rod L, the middle part of which passes over the truss-block M, and its end parts pass through and are secured to the said center bar. 85

To the projecting ends of the center bar of the follower K are attached bands N, upon which, at the tops of the said ends, are formed ribs or projections O, for the operating-levers P to engage with when placed above the said ends. 95

To the bands N, below the ends of the center bar of the follower K, are hinged rings Q, to receive the levers P when placed below the said ends. 100

Into the rings Q are hooked open links R, 105 provided with rings S, to receive the levers P when the follower is at the top of the press.

To the upper part of the ends of the press-

frame A are attached projecting arms T, to the outer ends of which are hinged the upper ends of the fulcrum-bars U, which have cross-pins V attached to them, as shown in Figs. 1, 5 2, and 3, or inclined slots V' formed in them, as shown in Fig. 4, to serve as fulcrums to the levers P. The lower ends of the fulcrum-bars U are connected with the base-frame of the press by link-connections X or other suitable 10 means. The engaging ends of the levers P are made of iron, and slotted to receive the edge of the fulcrum-bars U, and are curved upward slightly to take a secure hold upon the fulcrum-pins V.

15 Upon the lower sides of the engaging ends of the levers P are formed three (more or less) cross-grooves, P', to receive the ribs O or the rings Q or S, to prevent the said levers from slipping when power is applied to them, and 20 to allow the short arms of the levers P to be lengthened when less power and more speed are required, and shortened when more power and less speed are required. In case the slotted fulcrum-bars U V' be used, the forked ends 25 of the levers P should be provided with stationary cross-pins to enter the slots V', and thus engage with the said fulcrum-bars. With this construction, when a sufficient quantity of the substance to be baled has been placed 30 in the baling-box, the follower K is put on and forced down below the level of the top of the press, the strengthening-bars W are arranged in place, and the links R are hooked into the rings Q. The levers P are then inserted in 35 the rings S and operated until the follower K has been lowered sufficiently to bring the rings Q into convenient reach, and, finally, the said levers are placed upon the upper sides of the projecting ends of the center bar 40 of the said follower, the forked ends of the said levers being moved down upon the fulcrum-bars U after each stroke.

To the adjacent sides of the bars I, at the opposite sides of the slots in the ends of the 45 press, are attached ratchet-bars Y, with their teeth projecting outward for the cross-head outer ends of the catch-bars Z to engage with. The catch-bars Z slide in keepers a, attached to the parts of the center bar of the follower 50 K that pass through the slots in the ends of the press. To the outer ends of the catch-bars Z are attached small hooks b, upon which are hooked the outer ends of spiral springs c. The inner ends of the springs c are attached 55 to the truss-rod L, or other suitable support. With this construction, as the follower K is forced downward by operating the levers P the ends of the cross-heads of the catch-bars Z slide over the teeth of the ratchet-bars Y 60 and engage with the said teeth when the levers are being adjusted for another stroke, so as to hold the follower against being forced upward by the expansion of the substance being compressed. When the follower K is to 65 be raised, the outer ends of the springs c are detached, and the catch-bars Z are drawn out-

ward far enough to clear the teeth of the ratchet-bars Y; or the catch-bars Z can be drawn outward without detaching the springs c and secured in place by pins passed through 70 holes in the said catch-bars and into holes in the center bar of the follower K.

d are thin plates, of metal or other suitable material, made wider than the slots through the ends of the press, and with their forward 75 ends rounded. The plates d, after the baling-box has been filled with material for a bale, are inserted between the ends of the lower part of the follower K and the ends of the press, with their upper ends against the lower 80 side of the projecting end parts of the center bar of the said follower, so that the said plates will be forced downward by the said follower, and will cover the parts of the slots in the ends of the press, to prevent the material being compressed 85 from being forced outward through the said slots.

Having thus fully described my invention, I claim as new and desire to secure by Letters Patent—

1. A baling-press constructed substantially as herein shown and described, and consisting of the press-box having slotted ends and provided with ratchet-bars Y and fulcrum-bars U, the follower K, having truss L M and provided with spring-held catch-bars Z, and bands N, having ribs O and rings Q, and the levers P, having slotted and recessed forward ends, as set forth.

2. In a baling-press, the combination, with 100 the press-frame A and the center bar of the follower K, of the fulcrum-bars U, the bands N, having ribs O and rings Q, and the levers P, substantially as herein shown and described, whereby the said levers can be applied below 105 and above the said ends successively, as set forth.

3. In a baling-press, the combination, with the press-frame A, the center bar of the follower K, the fulcrum-bars U, the bands N, 110 having ribs O and rings Q, and the levers P, of the separable links and rings R S, substantially as herein shown and described, whereby the levers can be applied at a distance below the said center bar of the follower when 115 beginning the pressing operation, as set forth.

4. In a baling-press, the combination, with the slotted ends of the press and the center bar of the follower, of the ratchet-bars Y, on both sides of the slots, and the T-shaped catch-bars Z, sliding in bearings on the ends of the center bar of the follower K, and springs c, secured to the follower and slides, substantially as herein shown and described, whereby the follower will be held in place while adjusting the levers for another stroke, as set forth.

ANDREW JOHNSON.
